US00D754483S

(12) **United States Design Patent**
Elsaden et al.

(10) **Patent No.:** **US D754,483 S**
(45) **Date of Patent:** **** Apr. 26, 2016**

(54) **BEVERAGE CONTAINER**

- (71) Applicant: **Ignite USA, LLC**, Chicago, IL (US)
(72) Inventors: **Sami Elsaden**, Winnetka, IL (US); **Paul Hurley**, Libertyville, IL (US); **Bryan Washburn**, Buffalo Grove, IL (US); **Blair Miller**, Chicago, IL (US)
(73) Assignee: **IGNITE USA, LLC**, Chicago, IL (US)
(**) Term: **14 Years**
(21) Appl. No.: **29/513,508**
(22) Filed: **Dec. 31, 2014**
